2,154,692

ELECTRICAL COUPLING SYSTEM

Garrard Mountjoy, Bayside, Long Island, N. Y.,
assignor to Radio Corporation of America, a
corporation of Delaware

Application January 21, 1937, Serial No. 121,424

7 Claims. (Cl. 250—20)

An object of this invention is to provide a coupling system for connecting an antenna, and more especially a capacity type of antenna, to the input terminals of a radio receiver.

5 A more specific object is to provide an efficient coupling system wherein the capacity of the antenna is of small value such as in the case of a rod antenna when mounted on a vehicle such as an automobile, in which case the coupling 10 system may also be designed to prevent extraneous noise currents, such as those originating in the ignition circuits of the engine, from getting into the receiver.

15 A still further object is to provide a coupling system for an antenna which substantially increases the gain at the lower frequencies of the tuning range and thereby provides a more uniform gain over the entire tuning range than the usual type of coupling system commonly 20 used.

Further objects of the invention will become apparent to those skilled in the art as the description thereof proceeds. For a better understanding 25 of the invention, however, reference is made to the accompanying drawing in which;

Fig. 1 is a schematic circuit diagram of a coupling system embodying the invention and,

Fig. 2 is a curve showing the gain obtained 30 with a coupling system of the type shown in Fig. 1.

As shown in Figure 1, a rod antenna 1 composed of a short metal rod or other suitable type of capacity antenna is connected to a coil L_3 by a short lead 14 and through a coil L_2 to ground. 35 or a counterpoise 11. It will be understood that my invention is not limited to the use of a rod antenna as any known type of antenna may be used therein and more especially an antenna whose capacity is relatively small. As shown, the 40 antenna capacity with reference to ground is indicated by the dotted condenser of capacity C_a . The lower end of coil L_3 is connected by the lead-in wire 12, which is preferably enclosed within a flexible metallic shield indicated at 13, to one side 45 of a condenser C_c which provides capacity coupling between the antenna circuit and the resonant circuit including coil L_1 and its shunting condenser C_T . Condenser C_T is of the known adjustable type employing rotor and stator portions and is used in conjunction with coil L_1 to 50 form a parallel tuned circuit adjustable to resonate at the desired signal frequency. As shown, the output terminals 15 of the coupling system are connected to the control grid and cathode 55 of the radio frequency amplifying stage 10 of a

radio receiver, the other stages of which are not shown and may be of the tuned radio frequency type or of the superheterodyne type such as known to those skilled in the art.

The capacity between the lead-in 12 and ground, which includes the capacity between it and its enclosing shield 13 which is preferably grounded, is indicated by the dotted capacity C_L . I prefer to mount the coil L_3 closely adjacent to the antenna and coil L_2 in the same casing with 10 the radio receiver so that these coils are not inductively coupled although a small degree of inductive coupling between them would not materially alter the performance of the system. When used to receive modulated carrier signals 15 in the present broadcast band of 550 to 1500 kilocycles, the circuit constants are designed so that L_3 and C_a resonate at 1500 kilocycles or at a frequency slightly above this value and also C_a , L_3 , L_2 and C_L form a circuit resonant at 600 kilo- 20 cycles. Defining the gain as the ratio of the voltage developed across output terminals 15 to the voltage induced in the antenna by the received carrier wave, a coupling system designed as above gave the gains shown in the curve of Fig. 2 as the 25 tuning condenser C_T was adjusted for the several frequencies of the band. It will be noted that the gain does not fall off at the lower frequencies to as great an extent as when simple transformer coupling between the antenna and the resonant input circuit of the receiver is employed.

In this particular installation the circuit elements had the following values:

$C_a=11$ micro-microfarads	35
$C_L=30$ micro-microfarads	
$C_c=20$ micro-microfarads	
$L_1=250$ microhenrys	
$L_2=1800$ microhenrys	
$L_3=750$ microhenrys	

40 In an automobile installation the disturbing high frequencies radiated by the ignition system or other wiring circuits of the car and which may reach the antenna 1 may be prevented from reaching the receiver by designing coil L_3 to offer 45 a high impedance to currents of such frequencies, which are usually higher than the broadcast band. The coil should be preferably wound so that its windings or an appreciable part thereof, have a low distributed capacity. I also prefer to 50 make the coupling condenser C_c adjustable so that it may be set and function in the fashion of a trimmer condenser to adjust the resonant frequency of the circuit $L_1 C_T$ to a definite value at the high frequency end of the tuning range or 55

when tuning condenser C_T is set at its position of minimum capacity.

While I have described my invention in connection with a circuit tunable over the broadcast band of frequencies, it will be understood that it is equally adapted for use to connect an antenna to a circuit tunable over either a higher or a lower range of frequencies.

While I have described my invention in connection with a certain circuit, it will be understood that it is not limited thereto but includes all transmission circuits included within the scope of the following claims.

What I claim and desire to secure by Letters

15 Patent is:

1. In combination, a source of signal voltage having a predetermined capacity, a parallel resonant circuit tunable over a wide range of frequencies, a coil of low distributed capacity having 20 one end connected to said voltage source and having such an inductance value as to resonate with the capacity of said voltage source at a frequency of the order of the highest frequency of said range of frequencies and a condenser connected to the other end of said coil and to one end of said parallel resonant circuit.
2. In combination, an antenna having a substantially fixed capacity, a parallel resonant circuit tunable over a wide band of signal frequencies, a coil and condenser connected in 30 series between said antenna and the high potential end of said resonant circuit, said coil having low distributed capacity and forming with the antenna capacity a circuit having a resonant frequency at substantially the highest frequency of the band.
3. In combination, a source of signal voltage having a predetermined capacity, first and second coils connected in series between said voltage source and ground, the first of said coils being of 40 low distributed capacity and forming with the inherent capacity of said voltage source a cir-

cuit having a resonant frequency of the order of ω , a parallel resonant circuit tunable over a frequency range from ω to a substantially lower frequency and a condenser of small capacity having one side connected to the common terminal of 5 said coils and its other side connected to the high potential end of said parallel resonant circuit.

4. The arrangement of claim 3 in which said coils are separated to such an extent that there 10 is substantially no inductive coupling therebetween.

5. The arrangement of claim 3 in which said first coil is located in close relation to the signal source and is constructed to have an inductance 15 sufficiently high as to substantially prevent the transmission of currents of frequencies much higher than ω .

6. In a transmission network, the combination 20 of a source of signal voltage having a predetermined capacity, first and second coils connected in series between said source and ground, a parallel resonant circuit tunable through a band of frequencies, a condenser having one side connected to the high potential end of said parallel 25 resonant circuit, a lead-in connected between the other side of said condenser and the common terminal of said coils, the inductances of said coils being so designed that together with the inherent capacity of said voltage source and said 30 lead-in they form a circuit having a resonant frequency of the order of the lowest frequency of the band.

7. The arrangement of claim 6 in which the first coil is of low distributed capacity and has 35 such an inductance as to form with the inherent capacity of said voltage source a circuit having a resonant frequency of the order of the highest frequency of the band.
